Primary Examiner — Robin V Webster*(74) Attorney, Agent, or Firm* — Hodgson Russ LLP(57) **CLAIM**

The ornamental design for a swimming pool chlorine dispenser, as shown and described.

DESCRIPTION

FIG. 1 is a front-right-top perspective view of a first embodiment of a swimming pool chlorine dispenser showing my new design;

FIG. 2 is a front-bottom-left perspective view thereof;

FIG. 3 is a front elevational view thereof;

FIG. 4 is a rear elevational bottom view thereof;

FIG. 5 is a right side elevational view thereof;

FIG. 6 is a left side elevational view thereof;

FIG. 7 is a top view thereof;

FIG. 8 is a bottom view thereof;

FIG. 9 is a front-right-top perspective view of a second embodiment of a swimming pool chlorine dispenser;

FIG. 10 is a front-bottom-left perspective view thereof;

FIG. 11 is a front elevational view thereof;

FIG. 12 is a rear elevational bottom view thereof;

FIG. 13 is a right side elevational view thereof;

FIG. 14 is a left side elevational view thereof;

FIG. 15 is a top view thereof; and,

FIG. 16 is a bottom view thereof.
